US0D1067601S

(12) United States Design Patent (10) Patent No.: US D1,067,601 S
(45) Date of Patent: * Mar. 25, 2025

(54) FOOTWEAR UPPER

(71) Applicant: Wolverine Outdoors, Inc., Rockford, MI (US)

(72) Inventor: Brenton S. Wehrmeyer, Grand Rapids, MI (US)

(73) Assignee: Wolverine Outdoors, Inc., Rockford, MI (US)

() Term: 15 Years

(21) Appl. No.: 29/889,077

(22) Filed: Apr. 7, 2023

(51) LOC (15) Cl. 02-04

(52) U.S. Cl.

USPC D2/969; D2/916

(58) Field of Classification Search

USPC D2/916, 919–926, 929–946, 969–978

CPC A43B 1/10; A43B 1/14; A43B 3/00; A43B

3/10; A43B 3/12; A43B 3/14; A43B

3/0036; A43B 3/0042; A43B 3/101; A43B

3/126; A43B 5/00; A43B 5/06; A43B

5/10; A43B 9/14; A43B 9/16; A43B 9/18

See application file for complete search history.

(57) CLAIM

The ornamental design for a footwear upper as shown and described.

DESCRIPTION

FIG. 1 is a perspective view of a footwear upper embodying the new design;

FIG. 2 is a top view thereof;

FIG. 3 is a bottom view thereof;

FIG. 4 is a right side view thereof;

FIG. 5 is a left side view thereof;

FIG. 6 is a front view thereof; and,

FIG. 7 is a rear view thereof.

The figures show features in even broken lines that form no part of the claimed design. The dot-dash broken lines depict the bounds of the claim and form no part thereof.

1 Claim, 7 Drawing Sheets
